ELECTRICAL CONNECTOR

Robert J. Kinkaid, New Cumberland, Pa., assignor to
AMP Incorporated, Harrisburg, Pa.

Filed Sept. 26, 1963, Ser. No. 76,746

Term of patent 14 years

(Cl. D26—1)

FIGURE 1 is a perspective view of an electrical connector, showing my new design;

FIGURE 2 is a fragmentary top plan view;

FIGURE 3 is a fragmentary side elevational view, the opposite side being substantially a mirror image thereof;

FIGURE 4 is a fragmentary bottom plan view;

FIGURE 5 is a fragmentary front elevational view, to an enlarged scale; and

FIGURE 6 is a fragmentary front elevational view, to an enlarged scale, partly in cross-section taken on line 6—6 in FIGURE 3.

The essential features of the design reside in the portions shown in solid lines.

I claim:

The ornamental design for an electrical connector, as shown and described.
